UNITED STATES PATENT OFFICE.

WILLIAM P. CARTWRIGHT, DECEASED, LATE OF SCHENECTADY, NEW YORK, BY
MARTHA CARTWRIGHT, EXECUTRIX OF SAID WILLIAM P. CARTWRIGHT, AS
SIGNOR TO GENERAL ELECTRIC COMPANY, A CORPORATION OF NEW YORK.

HOLDER FOR HEAVY SHADES.

1,076,626.

Specification of Letters Patent.

Patented Oct. 21, 1913.

Application filed October 6, 1909. Serial No. 521,380.

To all whom it may concern:

Be it known that WILLIAM P. CARTWRIGHT, deceased, a citizen of the United States, late of Schenectady, in the county of Schenectady and State of New York, during his lifetime invented certain new and useful Improvements in Holders for Heavy Shades; and that I, MARTHA CARTWRIGHT, executrix of the estate of the said WILLIAM P. CARTWRIGHT, do hereby declare, to the best of my knowledge and belief, that the following specification, taken in connection with the accompanying drawing, forming a part of the same, is a clear, true, and complete disclosure of said invention.

This invention relates to incandescent electric lamps, and its object is to provide an improved holder for the heavy glass or porcelain shades which are now used with pendant high-powered lamps. The old method of supporting the shade has been to attach a shade holder to the shell of the lamp socket near its lower end so as not to interfere with the key of said socket. But this throws the entire weight of the shade and its holder upon the fastenings which secure the shell to the cap. As these fastenings are usually small and light, they are not suitable for supporting the large and heavy shades which are now coming into use, and hence the present invention aims to meet this difficulty by furnishing a yoke straddling the cap and having legs extending down the sides of the shell and attached to the shade holder, whereby the weight of the shade is thrown upon the cap instead of upon the shell.

Moreover, the invention comprises novel means for attaching the shade to the holder, consisting of a loose wire clamp sprung into the bell of the holder and having outwardly turned ends engaging with notches in said bell, so that said clamp can be locked after it has been contracted upon the neck of the shade. The clamp is loosely supported in the bell by its projecting ends and by loops projecting through slots in said bell.

In the accompanying drawing, Figure 1 is a side elevation, partly in section, of a shade holder embodying the invention; Fig. 2 is a bottom plan view, partly in section, and Fig. 3 is a perspective view of the yoke with its parts separated.

The lamp socket shown is of the usual construction, having a cap 1 to which is secured the shell 2. The shade holder 3 is spun out of sheet metal, having a flange 4 which surrounds and preferably fits snugly on the lower end of the shell 2, preferably abutting against a bead 5 thereon. The holder is supported by a yoke, which comprises a collar resting on top of the cap 1 and having two depending legs whose lower ends are attached to the holder. For convenience of manufacture, the yoke is preferably made in two parts, each comprising one half of the circular collar 6 and one of the legs 7. These parts are punched from sheet metal, one end of each collar portion having a hook 8 and the other end an eye 9, so that the two portions can be readily fastened together by engaging each hook with the eye in the other portion. The collar is shaped to lie smooth on the cap, and the legs may be bent irregularly to fit the outside of the cap and shell. The end of each leg has an outwardly-bent foot 10 in which is a screw-threaded hole to receive a screw 11 which fastens the leg to the shoulder 12 of the shade holder. To facilitate the attachment and removal of the holder, the screws 11 are passed through keyhole apertures 13 in the shoulder 12. This permits the holder to be engaged and disengaged by a bayonet-joint movement, without disturbing the yoke and the screws. If the socket has a long shell, spacing collars 14, surrounding the screws 11, may be inserted between the feet 10 and the shoulder 12.

Running around the inside of the bell 15 of the shade holder is a resilient clamping wire 16, which has one or more loops 17 projecting out through slots 18 in said bell. The wire is loose, that is to say, it is not attached to the bell at any point. Both ends 19 of the wire are free and are bent outwardly and pass, respectively, through the slots 20. The lower edge of each slot is provided with one or more teeth 21 with which the ends 19 can be engaged after they have been pinched together by the thumb and finger of the operator. Fig. 2 shows the resilient clamping ring wide open to permit the upper end of the shade 22 to be thrust up into the bell 15. When this has been done, the ends of the clamp are brought

toward each other and sprung in between the teeth 21, as shown in Fig. 1, and in dotted lines in Fig. 2. This contracts the clamp upon the neck of the shade, whose weight is supported by the loop 17 and the ends 19 resting in their slots 18 and 20. The shade can be released by disengaging the ends 19 from the teeth 21 and allowing the clamp to spring open.

10 In accordance with the provisions of the patent statutes, I have described the principle of operation of the invention, together with the apparatus which I now consider to represent the best embodiment thereof; but

15 I desire to have it understood that the apparatus shown is only illustrative, and that the invention can be carried out by other means.

What is claimed as the invention of the said WILLIAM P. CARTWRIGHT, is,—

20 1. In combination with an incandescent lamp socket, of a supporting yoke comprising a collar adapted to rest on the cap of the socket, legs depending from said collar along the sides of the socket, and a shade-holder connected to said legs and provided with a central aperture adapted to receive and engage the lower end of the socket.

25 2. A shade-supporting yoke for an incandescent lamp socket, comprising two portions each having a half collar provided at one end with a hook and at the other end with an eye, the hook of one half collar adapted to engage the eye of the other half collar, and a leg depending from each of said half collars and provided with a threaded opening.

30 3. The combination with an incandescent lamp socket, of a shade holder engaging the lower end thereof, and a yoke having a collar straddling the cap of said socket and provided with legs extending down the sides

of said socket and adjustably attached to said holder.

4. The combination with an incandescent lamp socket, of a yoke supported on the cap 45 of said socket and having legs extending down the sides thereof, and a shade holder seated upon the lower end of said socket and detachably secured to said yoke.

5. The combination with an incandescent 50 lamp socket, of a yoke supported on the cap of said socket and having legs extending down the sides thereof and provided at their lower ends with longitudinal screws, and a shade holder detachably secured to said 55 screws by bayonet joints.

6. The combination with an incandescent lamp socket, of a yoke supported on the cap of said socket and having legs extending down the sides thereof and bent at their 60 lower ends, screws in the bent lower ends of said legs, and a shade-holder seated upon the lower end of said socket and having key-hole apertures adapted to engage with said 65 screws.

7. A shade holder for incandescent lamp sockets comprising a bell to receive the upper end of the shade, and provided with slots, a loose open clamping ring of resilient wire having loops projecting through some of 70 said slots, and having outwardly extending ends engaging other slots, and a plurality of teeth in said last-named slots to lock said ends independently.

In witness whereof, I have hereunto set 75 my hand this 25th day of September, 1909.

MARTHA CARTWRIGHT,
Executrix of the estate of William P. Cartwright.
